Chamberlain & Newman Attorneys

UNITED STATES PATENT OFFICE.

ROBBINS N. GRISWOLD, OF BRIDGEPORT, CONNECTICUT.

CIRCUIT DISTRIBUTOR.

1,407,266.

Specification of Letters Patent. Patented Feb. 21, 1922.

Application filed February 11, 1920. Serial No. 357,913.

To all whom it may concern:

Be it known that I, ROBBINS N. GRISWOLD, a citizen of the United States, and resident of Bridgeport, in the county of Fairfield and 5 State of Connecticut, have invented certain new and useful Improvements in Circuit Distributors, of which the following is a specification.

This invention relates to circuit distributors such as are employed in connection 10 with internal combustion engines.

The object of the invention is to improve upon this class of devices by increasing the operative contacting surfaces and to form 15 said surface so as to provide a more positive engagement whereby a more reliable electric connection will be produced; further to design the device with a relatively few parts in a manner to form a simple and efficient 20 distributor.

With these and other objects in view the invention resides and consists in the construction and novel combination and arrangement of parts hereinafter more fully 25 described, illustrated in the accompanying drawings, and pointed out in the claim here-to appended, it being understood that various changes in the form, proportion, size and minor details of construction within the 30 scope of the claim may be resorted to without departure from the spirit or sacrificing any of the advantages of the invention.

Similar characters of reference denote like or corresponding parts throughout the several figures of the accompanying drawings forming a part of this specification, and upon which,

Fig. 1 shows a side elevation of my improved form of circuit distributor, and 40

Fig. 2 shows a sectional view of the same taken on line 2 2 of Fig. 1.

As illustrated in the drawings the mechanism of the apparatus is adapted to be contained within a commercial type of casing 45 adapted for use upon the cam shaft of certain well known types of cars. The parts, however, may be equally as well contained within other styles or forms of casings and upon other makes of engines.

Referring in detail to the characters of reference marked upon the drawings, 5 represents the metal casing referred to, which, as will be noted, comprises an annular cylindrical body portion, having one closed end 50 and an opposite open end. 7 indicates a cam shaft shown in dotted lines, and as rep-

resenting part of a motor, and upon the end of which the distributor is designed to be placed. The rotator 8 is secured to this shaft by means of a pin 9 and the hub portion of the rotator is obviously formed of metal as is also the radial extension 10 formed integral therewith. A metal shoe 11 is secured to this extension by means of screws as shown and is fitted into a peripheral recess of the insulating rim 12 secured upon the hub and in line with the metal shoe 11, so as to provide a continuous annular peripheral operating surface. This periphery of the distributor is of an irregular 70 shape in cross section, being preferably bevelled upon two sides forming an annular portion 13 of a greater diameter than the remaining surfaces 14 to form a broader operating face on the distributor than would 75 be possible were it provided with a flat face.

In connection with this central rotor I provide a series of contacting rolls 15 the faces of which are substantially V-shaped to correspond with the operating peripheral 80 surface of the rotator. There may obviously be any desired number of these contacting rolls which are suitably spaced one from the other to ride upon the periphery of the rotator. Each of these rolls are mounted in 85 a bracket 16 that is preferably formed of spring sheet metal and whose inner ends are shaped to conform to the shape of the inner wall of the cylindrical portion of the casing, and is tensioned to form a yieldable 90 pressing engagement on the periphery of the rotator. 17 represents an insulating member which is positioned between the bracket and the casing and 18 represents a screw that passes through the bracket and 95 the insulating member as well as the insulating washer 19. 20 represents a nut mounted upon each screw for securing the parts together and 21 indicates binding nuts by means of which the feed wires 22 are attached.

From the foregoing it will be seen that in view of the V-shaped peripheral engaging surface of the rotator and rolls I obtain a longer and rubbing connection between the 105 same which insures a better electrical contact and forms a more durable construction.

Having thus described my invention, what I claim and desire to secure by Letters Patent, is:

A circuit distributor including a rotatable shaft having an integral radial extension, a

rotor on said shaft having an annular V-shaped peripheral face formed of insulating material and having a metal contact insert, the metal insert extending outwardly 5 to form a section of the annular V-shaped peripheral face and extending inwardly for engagement with said radial extension, contact rolls, the faces of said rolls being grooved to permit the reception of the pe-

ripheral face of said rotor, a cap, and springs 10 for connecting said rolls and cap.

Signed at Bridgeport in the county of Fairfield and State of Connecticut this 6th day of February, A. D., 1920.

ROBBINS N. GRISWOLD.
